TOY BUG

David W. Jones, Glencoe, and Bayard C. Reed, Chicago,
Ill.; said Reed assignor to Marvin I. Glass, Chicago, Ill.

Application January 17, 1957, Serial No. 44,513

Term of patent 14 years

(Cl. D34—15)

We claim:

The ornamental design for a toy bug, substantially as shown and described.
